US00D719586S

(12) United States Design Patent
Jon

(10) Patent No.: US D719,586 S
(45) Date of Patent: * Dec. 16, 2014

(54) DISPLAY SCREEN OR PORTION THEREOF
WITH ICON

(75) Inventor: Tiffany Jon, Cupertino, CA (US)

(73) Assignee: Apple Inc., Cupertino, CA (US)

() Term: 14 Years

(21) Appl. No.: 29/424,260

(22) Filed: Jun. 8, 2012

(51) LOC (10) Cl. 14-02

(52) U.S. Cl.

USPC D14/495

(58) Field of Classification Search

CPC G06F 3/04817; G06F 3/0482

USPC D14/489-495; D20/25, 31-33

See application file for complete search history.

(57) CLAIM

The ornamental design for a display screen or portion thereof with icon, as shown and described.

DESCRIPTION

The FIGURE is a front view of a display screen or portion thereof with icon showing my new design.

The broken lines around the FIGURE showing a display screen or portion thereof form no part of the claimed design.

1 Claim, 1 Drawing Sheet
